UNITED STATES PATENT OFFICE

MAURICE COPE, OF KINGSLEY, AND ERNEST W. PAULSON, OF HINTON, IOWA

SELF-CLOSING DOOR

Application filed May 18, 1931. Serial No. 538,026.

Our invention relates to self-closing doors of the type disclosed in the Cope Patent No. 1,570,462, issued January 19, 1926, and has for its object generally to improve upon the 5 invention of said patent.

More particularly, it is our object to provide a structure wherein the primary closure elements are mounted so that less lifting pressure is required for opening them than in the 10 structure of the Cope patent.

A further object of this invention is to provide in a structure of this character, an arrangement for adjusting the primary closure members so that their meeting edges 15 will snugly register when the door is closed.

A further object is to provide, in a door of the type of the Cope patent, an auxiliary closure structure wherein the auxiliary closure members are mounted so that they can- 20 not be broken off. In this respect, it may be stated that it has been found that a sudden rush from within against the auxiliary closure members by a small pig is capable of breaking off one or both of these auxiliary closure members, or of loosening them on 25 their mountings so as to render their operation imperfect.

A further object is to provide in a structure of the type under consideration, a pair 30 of auxiliary closure members so constructed that their inner edges cannot possibly injure the sides of a pig when the latter is passing between them, and yet which are of relatively simple, and durable construction.

Another object is to provide in a door of 35 this type, an arrangement whereby when the door is closed there will be no exposed cracks or spaces for the entrance of cold air into the housing structure closed by the door.

A further object of the invention is to provide a door having the above characteristics, and yet which is of very simple, durable, and inexpensive construction.

45 With these and other objects in view, our invention consists in the construction, arrangement, and combination of the various parts of our device, whereby the objects contemplated are attained, as hereinafter more 50 fully set forth, pointed out in our claims,

and illustrated in the accompanying drawing, in which:

Figure 1 is a front elevation of the door,

Figure 2 is a plan view of the same,

Figure 3 is a front elevation of the door 55 in open position,

Figure 4 is a central, vertical, sectional view through the door.

Figure 5 is an enlarged, detail view of 60 one of the auxiliary member mountings, 60

Figure 6 is a detail, sectional view through 65 the upper end of one of the auxiliary closure members.

The door of this invention comprises a 70 doorway constructed with the upright posts or battens 10 and the casing members 11 and 12 which are cut away to con-jointly form the door opening 13.

A metal reinforcing member 15 is secured 75 horizontally to the casing member 11 near its upper edge and serves as a bracket for supporting the door hangers 16 and 17. The member 15 has the portions 14 disposed forwardly of the plane of the portions 15 which are secured as at 18 to the casing member 11, and to these forward portions 14, the hangers 16 and 17 are pivoted as at 19 and 20.

To the lower ends of the hangers 16 and 80 17 are pivoted as at 21 and 22 respectively the primary closure members 23. The pivots 21 and 22 are parallel to the pivots 19 and 20, thereby causing the closure members 23 to swing in constantly parallel relation- 85 ship to each other.

In order to keep the primary closure members 23 adjusted so that they are exactly parallel and so that their inner edges will register snugly when closed, the hangers 17 90 are made adjustable for length. Any approved telescoping or turn-buckle type of construction might be employed although we prefer, for simplicity, to use the construction shown wherein one end of each hanger 17 95 is a rod as shown, threaded as at 24 and wherein the other end of the hanger is an L shaped piece of strap metal 25 perforated to receive the threaded rod portion 24, and secured thereto by nuts 26 and 27 engaging 100

either side of the perforated portion of the member 25.

The lower regions of the primary closure members 23 are cut away as at 28 to form between them, a tri-angular shaped opening. A filler block 29 is secured to the casing member 12 near the bottom thereof and its side edges are inclined at the angle of the cut-away edges 28 and just the right distance apart to substantially engage the lower extremities of said edges 28 when the primary closure members are closed.

Guide straps 30 are secured to the filler blocks 29 and to the casing member 12, being provided with shoulder portions 31 spacing their outer extremities away from the casing member 12 a distance substantially greater than their spacing at their inner ends. At their inner ends, the guide straps 30, being secured flatly against the filler block 29, will engage the primary closure members 23 to hold them snugly against the casing member 12. In their outer regions however, the guide straps 30 are sufficiently spaced so that there will be no friction between the closure members and the guide straps such as to retard the swinging action of the doors.

In operation, assuming the doors to be opened as shown in Figure 3, and then to be released, allowed to swing back to closed positions, they will attain sufficient momentum in thus swinging to wedge themselves securely between the straps 30 and casing member 12 at the inner limits of their swings. Thus they will be held securely in snug engagement with the casing member 12 so as to close the opening 13 against the admission of cold air, and yet very little outward pressure will be necessary to disengage them from this wedging fit and to again move them outwardly toward open position.

Owing to the fact that the closure members swing parallel to each other, the extent of movement required to completely open them is only that necessary to bring the lines of their perpendicular inner edges to register with the side extremities of the door opening 13. In the old type of door wherein the primary closure members were pivoted to swing in arcuate paths, the closure members would have to swing upwardly to almost horizontal positions before the door opening 13 would be completely disclosed. To put the matter inversely, assuming the old pivoted closure members to have been swung to positions where their centers of gravity have been lifted the same distance as is sufficient to fully open the closure members of the present invention, their upper extremities would overlap the door opening and provide a triangular shaped opening very narrow at the top.

In the old style of door, if an animal large

enough to require substantially all of the space of the door opening for passage were to go through the door, the lifting of the closure members to the necessary height would cause them to bear with considerable pressure against the back of the hog, and the region of bearing would move toward the pivots of the closure members as the latter were moved higher. But as the regions of bearing moved toward the pivots of the closure members, the pressure of the closure members against the back of the hog would be multiplied by the increased height of the closure members and by the greater leverage caused by the moving of the points of contact closer to the fulcrums around which the weights of the closure members were exerted.

The present invention reduces the pressure of the closure members against the back of a hog to such an extent that the animals may pass through the door with very little difficulty. This is due partly to the fact that the door becomes fully opened when the closure members have moved relatively short distances and partly due to the fact that the areas of contact do not shift upwardly.

Turning now to the auxiliary closure members, each is formed of a sheet of metal including the body portion 32 rolled back upon itself as at 33 to provide a rolled edge, and extended as at 34 and secured as at 35 to the body portion 32. The beads 36 on the opposite edge of the body portion 32 are for reinforcing purposes.

In the old style of structure wherein the rolled edges 33 were terminated in a sharp edge, it was possible for a pig to injure itself against this edge, but by providing the extension 34 and securing it to the body portion as at 35, the sharp edge is eliminated, and the rolled portion is reinforced and braced.

Each auxiliary closure member is provided at its upper end with a hinge including the hinge leaf 37 secured to the body portion 32 and the hinge leaf 38 secured to the primary closure member 23. The leaves 37 and 38 are provided respectively with hinge sleeves 39 and 40 which register with each other and are connected by a hinge pin 41 which is bent back upon itself as at 42 to provide a projecting portion 43 around which is coiled a hinge spring 44. One end 45 of the spring 44 engages beneath the pin portion 42 and the other end 46 engages against the pin leaf 37.

It will now be seen that the action of the spring is such as to retain the extended pin portion 43 in a position above the hinge loops and at the same time to exert inward pressure against the auxiliary closure member so as to urge it flatly against the primary closure member 23.

The hinge leaf 38 is pivoted as at 47 to the primary closure member 23, and a stop

48 limits movement of the auxiliary closure member inwardly beyond a position wherein its rolled edge 33 is perpendicular.

It will now be seen that the auxiliary closure members may swing laterally parallel to the doorway, and at the same time may swing outwardly away from the plane of the doorway. The advantage of this arrangement lies in the fact that a sudden rush from a pig from within the housing structure will merely push the auxiliary closure members away from the door.

A further advantage is the fact that in pushing the auxiliary closure members away from the door, it becomes easy for the pig to make a preliminary opening between the members through which his snout may be inserted, and further pressure will result in pivotal swinging movement of the auxiliary members.

The auxiliary closure members overlap the filler block 29 at their lower ends and thus complete closure against the entrance of cold air is provided.

25 Some changes may be made in the construction and arrangement of the parts of our invention without departing from the real spirit and purpose of our invention, and it is our intention to cover by our claims 30 any modified forms of structure or use of mechanical equivalents which may be reasonably included within their scope.

We claim as our invention:

1. In a self-closing door, a doorway, a pair 25 of closure elements, arranged in side by side relationship, a pair of hangers suspending each closure element from the doorway, each hanger being pivoted at its lower end to a closure element and at its upper end to the doorway, the parts being arranged so that the closure elements will maintain substantially upright positions while swinging laterally to disclose the door opening.

2. In a self-closing door, a doorway, a pair 45 of primary closure elements mounted upon said doorway in side by side relationship and movable away from each other to disclose the door opening, the lower corners of said primary closure elements being cut away to provide between them an auxiliary opening, a pair of auxiliary closure elements, and means suspending said auxiliary elements from the primary closure elements, said means comprising hinges secured to the auxiliary closure elements and pivoted to the primary closure elements to allow the auxiliary closure elements to swing in their common plane away from each other, the axes of said hinges being parallel to said common plane so as to allow said auxiliary closure elements to swing away from the primary closure elements in directions transverse to said common plane.

3. In a self-closing door, a doorway, a pair 65 of primary closure elements mounted upon

said doorway in side by side relationship and movable away from each other to disclose the door opening, the lower corners of said primary closure elements being cut away to provide between them an auxiliary opening, a pair of auxiliary closure elements, and means suspending said auxiliary elements from the primary closure elements, said means comprising hinges secured to the auxiliary closure elements and pivoted to the primary closure elements to allow the auxiliary closure elements to swing in their common plane away from each other, the axes of said hinges being parallel to said common plane so as to allow said auxiliary closure elements to swing away from the primary closure elements in directions transverse to said common plane, and resilient means urging said auxiliary closure elements into face to face contact with the primary closure elements.

4. In a self-closing door, a doorway, a pair of primary closure elements mounted upon said doorway in side by side relationship and movable away from each other to disclose the door opening, the lower corners of said primary closure elements being cut away to provide between them an auxiliary opening, a pair of auxiliary closure elements, and means suspending said auxiliary elements from the primary closure elements, said means comprising a pair of hinges each including a hinge leaf secured to an auxiliary closure element and provided with a hinge sleeve, a hinge leaf pivoted to the corresponding primary closure element and provided with a hinge sleeve, a hinge pin received through both of said sleeves and bent back upon itself to form a hooked portion, and a coil spring receiving said hooked portion, one end of the spring being engaged against the hinge leaf which is secured to the auxiliary closure element and the other end of said spring being caught beneath the bent portion of the hinge pin.

5. In a self-closing door, a doorway, a pair of primary closure elements mounted thereon in side by side relationship and movable away from each other to disclose the door opening, the lower corners of said primary closure elements being cut away to provide between them an auxiliary opening, a pair of auxiliary closure elements mounted on said primary closure elements in side by side relationship and movable away from each other to disclose said auxiliary opening, and a filler block secured to the door opening, positioned to fill the space between the lower edges of the primary closure elements, the auxiliary closure elements overhanging said filler block.

6. In a self-closing door, a doorway, a pair of closure elements mounted thereon in side by side relationship for movement away from each other to disclose the door opening, and a pair of guides secured to the doorway,

spaced therefrom, and overlapping the lower ends of the closure elements, the spaces between said guides and the doorway being narrowed progressively from the outer extremities to the inner extremities thereof so as to provide a wedging fit for the lower ends of the closure elements at the inner ends of said spaces and to allow the closure elements to swing freely in the outer regions of said

10 spaces.

7. In a self-closing door, a doorway, a pair of primary closure elements, arranged in side by side relationship, a pair of hangers suspending each primary closure element from the doorway, each hanger being pivoted at its lower end to a closure element and at its upper end to the doorway, the parts being arranged so that the closure elements will maintain substantially upright positions

15 while swinging laterally to disclose the door opening, the lower corner of said primary closure elements being cut away to provide between them an auxiliary opening, and a pair of auxiliary closure elements pivoted at

20 their upper ends to the primary closure elements and depending in side by side relationship to close said auxiliary opening, said auxiliary closure elements being formed of sheet metal, and each on its inner side being

25 bent back upon itself to provide a rolled portion, the edge portion thereof being in contact with the main body portion of the auxiliary closure element and secured thereto.

Signed at Sioux City, Iowa, this 12th day
35 of May, 1931.
